UNITED STATES PATENT OFFICE

2,128,575

DRIVING MEANS FOR CENTRIFUGAL MACHINES

Eugene Roberts, Hastings, N. Y., assignor to The Western States Machine Company, Salt Lake City, Utah, a corporation of Utah

Application January 31, 1936, Serial No. 61,835

14 Claims. (Cl. 210—71)

This invention relates to new and improved centrifugal apparatus for use in the centrifuging of sugar and like materials, and it is intended to provide means for driving suspended gyratory centrifugals of the type used in sugar refineries at considerably higher speeds than has heretofore been the practice, while at the same time enabling a much quicker rate of acceleration which I have found to be an important factor 5 in the successful and practical operation of high speed centrifugals for sugar and analogous work.

Heretofore, under the best commercial practice, sugar centrifugals employing the prevalent 40" basket have been operated at a top speed 15 of from 1100 to 1200 R. P. M. either by means of a quarter turn belt passing over a pulley on the basket spindle or by means of an overhead electric motor directly connected to the spindle. When charged with its full load, each centrifugal 20 weighs approximately one ton, and even at the speeds above mentioned it is necessary in the case of the directly connected motor driven centrifugal to use a very much oversize motor to effect satisfactory results. A well designed centrifugal can be accelerated slowly to a speed under 25 1200 R. P. M. by means of an electric motor consuming approximately 20 horsepower, but to obtain the desired higher rate of acceleration would require a consumption of power rising as high as 30 60 horsepower, with peak power loads much higher under certain conditions. In consequence of these requirements, motors must be built very much oversize, which means heavy additional expense and difficulties in installation and further 35 more involves a wasteful expenditure of power. To raise the speed of the centrifugal still further and quicken its acceleration would greatly aggravate the difficulties incident to the use of directly connected electric motor drives. On the 40 other hand, any marked increase of speed and acceleration with belt driven machines would require the use of wider, heavier belts which, in view of their being of the quarter turn type, are also subject to practical objections, and it would 45 impose other severe operating requirements on such machines which are inconsistent with their operating capacity.

A further important disadvantage of the apparatus heretofore used consists in the fact that 50 after the centrifugals are installed for a certain type of operation, it is extremely difficult to vary their operation to any substantial extent. The apparatus has not been characterized by flexibility such as I have found to be important for 55 best processing operations, nor has it been readily

adaptable for various conditions of installation.

I have found that the speed and acceleration of gyratory centrifugals may be greatly increased while rendering their operation entirely safe and satisfactory from both an economical and a mechanical point of view by providing a new arrangement of powering, power transmission and coupling means intermediate a source of power and the basket spindles of several centrifugals. I have found also that an individual centrifugal 10 may be improved for flexibility of installation and operation and for operation at high or low speeds, with or without unusually rapid acceleration to such speeds, by providing it with an improved driving unit in accordance with my invention. 15

A preferred general arrangement of apparatus in which the present invention is embodied comprises a horizontal line shaft positioned above or adjacent a series of suspended gyratory centrifugal machines, each of which is independently 20 driven from the same line shaft through a power transmitting mechanism, preferably a centrifugally actuated clutch, and an intermediate driving unit including a train of transmission gears. One of the transmission gears is connected with a 25 rotatable driving member which, in turn, is connected with a pulley for the clutch or with other power transmitting means. Another is secured to a vertical non-gyratory transmission shaft having a flexible but positive driving connection with the 30 underneath gyratory centrifugal shaft or spindle.

An important feature of this general arrangement is that it permits substantial power savings in the operation of a series of centrifugals at high speeds and with rapid acceleration to such 35 speeds. The cycle of treatment of materials such as mixtures of sugar grains and syrup involves, braking, unloading, reloading and acceleration of some of the centrifugals of a series while others are spinning at full speed. During the 40 braking, unloading and reloading stages of the cycle, the centrifugal does not exert a substantial drain on the power source. During the acceleration stage, however, the power per centrifugal rises abruptly to its highest point, and it later tapers down to a normal amount after full speed 45 has been attained. My improved arrangement of centrifugals, driving units and power transmitting means on a common line shaft greatly reduces the power peak normally required for acceleration 50 of each centrifugal, due to the strong momentum of the line shaft and heavy parts revolving therewith together with that of the several centrifugals of a series which revolve in unison at high speed while the acceleration takes place. 55

In addition to the aforesaid novel general arrangement of centrifugals and centrifugal driving means, my invention provides an improved driving unit for connecting each of the centrifugals with a source of power, which is of importance because of its usefulness in either a group drive or an individual driving arrangement. This improved driving unit comprises an enclosing casing which is accurately machined to provide a mounting for the essential moving parts of the unit, including the train of intermeshing gears referred to above. A rotatable driving member is mounted within the casing and provided with an extension projecting outside of the casing for connection with another rotatable member, for example a pulley or shaft through which power is transmitted. A bevel gear is keyed to this first rotatable member. A transmission shaft is mounted within the casing with its axis at an angle to the axis of the rotatable driving member, and this shaft carries a bevel gear in accurate mesh with the bevel gear first mentioned. The transmission shaft has an extension which projects outside the casing and is positively and constantly coupled to the gyroscopic spindle of the centrifugal. In conjunction with the parts mentioned, the unit comprises suitable bearing members within the casing arranged for precise alignment and smooth operation of these parts, and the casing includes means facilitating attachment of the unit to framework above the centrifugal.

By the use of a driving unit of this type substantial improvements may be obtained in centrifugal operations. The source of power, of whatever nature, may be arranged to one side of the basket spindle to provide a more satisfactory plant arrangement. The powering means may be changed without reconstructing the unit or the centrifugal spindle or intermediate couplings. The unit may be moved and attached to the conventional motor base for a directly-driven centrifugal, or to any other suitable framework, without danger of misalignment of its moving parts and consequent difficulties, because a proper setting of the bearings, rotatable driving member, gears and transmission shaft remains accurate and insures precise operation for an indefinite period. It may be constructed with any gear ratio appropriate to the power and speed of the power transmitting means with which it is connected and the desired speed of the basket, and it fully withstands the continual severe strains of rapid acceleration to high speeds and short operating cycles.

A further improvement in driving construction resides in the construction of the line shaft in individual sections, one for each centrifugal mounted in its own individual bearings and flexibly coupled to adjacent sections, thereby permitting the removal of one shaft section without disturbing the other line shaft sections.

Another feature of the present invention is the provision for driving the line shaft from a powering device located intermediate the series of centrifugals whereby the centrifugals on one side of the powering device may be maintained in normal operation, while a centrifugal on the other side may be removed for repairs or replacements without stopping the centrifuging of the massecuite or magma. This is an important feature of advantage because should an accident happen, which ordinarily would require the stopping of the line shaft, the massecuite in the overhead mixer trough, which supplies the centrifugals, might become set or hardened while awaiting the com-

pletion of the repairs, and this would mean much difficulty and expense in digging out the hardened massecuite before the centrifugals could be started in operation with a fresh batch of massecuite.

These and other improvements will be particularly described in the following specification and will be defined in the claims hereto annexed.

In the accompanying drawings is illustrated a practical and efficient embodiment of my improvements, in which

Fig. 1 is a small scale elevation showing the arrangement of a battery of centrifugal machines operated from a common sectional line shaft with a powering motor for the shaft located intermediate of the group of centrifugals.

Fig. 2 is a vertical central section through the driving mechanism of a single centrifugal.

Fig. 3 is a front elevation of the construction shown in Fig. 2.

Fig. 4 is a detail cross section showing the coupling between the vertical non-gyroscopic transmission shaft and the basket shaft, as well as the brake and the brake drum.

Fig. 5 is an end elevation on the plane 5—5 of Fig. 2 further illustrating the driving mount of the centrifugal.

According to the specific construction and arrangement shown in the drawings there is provided a horizontal line shaft 1, which is made in individual sections for each centrifugal, which sections are coupled together as shown at 2 by any suitable type of flexible transmission coupling members, and each line shaft section is supported in anti-friction bearings contained in suitable housings or containers 3 and 4 provided with closure caps or covers 3^a, 4^a. The housing 3 for supporting one end of a shaft section, the right hand end as shown in Fig. 2, is supported in a hollow casing 5 whose opposite sides are provided with annular bearing seat members 5^b and 5^c, respectively, for the insertion and removal of anti-friction bearing elements. The casing 5 forms an upstanding hanger whose bottom portion or bed 5^d is provided with means enabling it to be accurately positioned and bolted upon a bed plate 6, which is provided at its left hand end with an upstanding supporting bracket 6^a on which the bearing housing 4 is secured. Thus each shaft section is supported near its opposite ends by supporting members projecting upwardly from a common bed plate which is mounted upon and secured to suitable longitudinal beams *a* and cross-beams *b* that are usually found in the framework of centrifugal apparatus beneath the sloping overhanging portion of the mixer trough of the centrifugal apparatus, which it is unnecessary to show herein as it is an old feature of sugar centrifugal apparatus construction.

The casing 5 forms the enclosure and mounting of a precisely machined and assembled driving unit which permits displacement of the power transmitting means to a point laterally of the centrifugal and effects a positive connection between said means and the basket spindle such that severe strains of rapid acceleration and high speed operation on short cycles will not interfere with the freedom of the spindle to gyrate and seek its own axis of rotation. This improved driving unit includes a rotatable driving member which is keyed to a bevel gear inclosed within the casing and provided with a portion extending outside the casing for attachment to the power transmitting means, together with a vertically positioned non-gyroscopic transmission shaft 75

provided with bearings and bearing seats in parts of the casing structure and having a portion extending outside the casing for attachment to flexible coupling elements intermediate the driving unit and the gyratory basket spindle, and another bevel gear keyed to this transmission shaft and located in accurate meshing relation to the bevel gear first mentioned. The construction of the unit as embodied in the improved group driving arrangement illustrated in the drawings is described in further detail below, but it will be understood by persons skilled in the art that details of construction employed in this particular arrangement are not essential to the invention and may be varied within the scope of the claims.

In the illustrated apparatus, the casing 5 for each driving unit is provided with structure cooperating with parts of a liquid cooled clutch pulley forming an element of the power transmitting means for each centrifugal and secured to the extended portion of the above mentioned rotatable driving member. Outside of annular flange 5^c is an annular flange 7 integral with, or secured to, the casing 5, the opening of this flange being considerably larger than the opening in the flange 5^c, which it surrounds concentrically, to permit the projection through it of an annular flange 8^a forming part of the hollow pulley 8, which is loosely mounted about the shaft section 1 for free rotation thereon. The rim portion of the pulley 8, as well as the spider portion 8^b, are both made hollow for the circulation of cooling liquid which enters through a supply pipe 60 and whose outlet is through the annular passage between the flange 5^c of the casing and the flange 8^a of the revoluble clutch pulley. The space between the annular flange 7 and the adjacent wall of the casing forms a receptacle or spill-way into which the cooling liquid flows after having performed its cooling function and from which it may be drawn off and cooled for recirculation. This cooling of the pulley, however, forms no part of the present invention herein claimed and is claimed in a copending application, so that more detailed description thereof is unnecessary here.

Between the line shaft 1 and the driving unit of each centrifugal means are employed which may be controlled to establish power transmitting connections of progressively increasing transmitted speed and thereby to effect smooth acceleration of the centrifugal notwithstanding constant rotation of the line shaft at full speed, as well as to establish a positive non-slipping connection which couples the driving unit, and through it the basket-carrying spindle, with the line shaft for rotation in unison at full speed. The illustrated means for forming such a connection between the continuously rotating line shaft 1 and the loose pulley 8 is in substance like the clutch mechanism shown and described in my Letters Patent of the United States No. 1,184,873 granted October 25, 1932, so that full description thereof in this application is unnecessary. The clutch mechanism comprises a radial arm spider 10 fastened on the line shaft 1, on which arms are fulcrumed oppositely disposed pivotal shoe-carrying arms 15 on which are pivotally mounted friction shoes 16 which under centrifugal force press outwardly powerfully against the interior face of the rim of the pulley 8. To retract the clutch shoes from engagement with the pulley rim there is also fulcrumed on the spider a pair of retracting arms 11, which are connected with the shoe-carrying arms 15 by

means of retracting links 14, so that when the free ends of the arms 11 are moved inwardly by the toggle links 12 fulcrumed to the sliding hub member 13 the shoe-carrying arms 15 are drawn inward, thus separating the friction shoes from the pulley rim. The hub member is forced inwardly to effect retraction of the clutch shoes by means of a lever 17 fulcrumed at 17^a, whose upper end is forked to engage opposite sides of a collar 13^a which is anti-frictionally mounted on the hub 13 to permit it to resist rotation by reason of its engagement or connection with the fork portion of the arm 17. The lower end of the lever 17 is provided with a toothed sector 18 meshing with a pinion 18^a on the control shaft 19 which carries a hand wheel 19^a by which it can be operated in starting the machine and setting in action the automatic timing mechanism disclosed in my pending application Serial No. 732,114, the details of which are not claimed herein but form, in part, the subject matter of the said pending application.

The spider of the clutch pulley 8 is secured to a rotatable driving member for the driving unit, in this embodiment an elongated sleeve or hub 25 surrounding the shaft 1 and mounted on bearing supports precisely positioned in the bearing seats 5^b and 5^c of casing 5. A large bevel gear 30 is splined to driving member 9 inside the casing 5 so that it rotates when the clutch pulley 30 is energized by engagement of the centrifugally actuated clutch shoes 16 with the rim of the pulley 8.

Directly beneath the line shaft 1 is located the vertical non-gyratory transmission shaft 32 of 35 each driving unit which carries at its upper end a smaller bevel pinion 31 intermeshing with the much larger bevel gear 30. This vertical transmission shaft 32 is mounted in upper and lower anti-friction bearings, accurately fixed within 40 casing 5, for rotation about a constant axis, and it is provided at its lower end with means for connecting it directly to positive but flexible coupling elements for a gyratory basket spindle. Thus a flange integral with the lower end of the 45 shaft is connected to downwardly projecting clutch of coupling fingers 32^a, and these are interposed between similar fingers 33^a of a coupling member 33 fastened to the projecting upper end of the gyratory centrifugal basket spindle 40 in order to connect shaft 32 and spindle 40 together. This coupling forms a positive drive connection 50 between the non-gyratory transmission shaft 32 and the gyratory centrifugal shaft 40, which latter in accordance with well known practice is carried by combination thrust and radial bearings 41 mounted on the outside of a tubular suspender 34 having a spherical supporting ball 35 seated in a socket in the fixed hanger 36, which is secured to a depending hanger member 6^b forming a downward extension of the bed plate 6. It will therefore be seen that the shaft section and the drive transmission mechanism for each centrifugal, as well as the centrifugal itself, are carried by a unitary supporting structure so that, when the flexible joint couplings 2 are disconnected, the whole bed plate with its supporting members can be removed after the hanger 36 with the centrifugal has been disconnected from the depending hanger element 6^b of the bed plate.

Any slight variation 60 in perfect alignment of the shaft sections is taken care of by providing flexible joint couplings 2 which may be of any well known type of construction. It will also be seen that, in the illustrated form of apparatus, driving coupling between the 65

fingers 32^a and 33^a takes place substantially in the plane of the center of gyration of shaft 40, which is located at the center of ball 35 and its supporting socket.

An outer meber 42 on the basket suspension shaft 40 carries a rigidly and removably attached brake pulley 43 embraced by opposite brake bands 22 which are contracted to braking position or expanded to inactive position by means of a vertical spindle 23 carrying at its upper end a crank arm 21, which is connected by intermediate link members with a crank arm 20 secured to the control shaft 19 which carries the hand control or starting wheel 19^a. Since the details of this control mechanism are explained in my copending application Serial No. 732,114 and are not herein claimed, it will suffice to explain how the control is exerted to energize and to stop the centrifugal. Assuming one of the centrifugals to be at rest after having been unloaded so that it is ready to be re-charged, the attendant throws the hand wheel 19^a and the control shaft 19 in a clockwise direction, thus effecting at the same time the releasing of the centrifugally actuated clutch shoes from their inactive position to their active position in engagement with the pulley rim 8. At the same time, through the crank arm 20 on that shaft and the crank arm 21 secured to the vertical brake spindle by intermediate link connections, the brake shoes are freed from engagement with the brake pulley 43 and the centrifugal begins to rotate with increasing speed. During the initial part of starting the centrifugal in operation, a charge of sugar is loaded into the centrifugal basket 45 in accordance with well known practice and rapidly builds up into a ring or wall of even thickness inside the basket. At the same time, through another connection at 26, the timing mechanism is started which controls the timing of the different operations of the centrifugal, as explained in my copending application mentioned above. Through the timing control, after a given interval of acceleration of the centrifugal, the spray is turned on for a further time regulated interval and, the centrifugal, still accelerating, the moisture is rapidly expelled and the sugar dried to the desired degree. Next the control shaft 9 is released and returned to initial position by means of the torsion spring 21, and practically at the same instant the line shaft clutch is released and the brake is set to stop the revolution of the centrifugal.

It will be noted that bevel gear 30 of the driving units is of relatively large diameter in comparison with the bevel pinion 31 secured to the underneath transmission shaft. No exact ratio is prescriptive, since the gear ratio will vary according to the type of powering means used to drive the centrifugals, but in practice very satisfactory results are obtained in a general arrangement of the type illustrated by driving the line shaft at from 400 to 450 R. P. M. and making the ratio of gears approximately 3½ to 1, or slightly greater. Thus there is a large diameter of driving gear and a correspondingly large diameter of clutch pulley which, in view of the special type of power transmission, results in a very rapid and powerful pick-up without shock or jolt or chattering. Speeds are obtainable with this construction and arrangement that could be only attained at great difficulty and at much expense through an overhead directly-connected motor, or by means of the usual quarter turn driving belt. The variability of powering means and gear ratios and consequently, of speeds and

rates of acceleration, also lends important advantages to the arrangement. By providing, intermediate the series of centrifugals driven from the line shaft, a powering element, which as shown at 28 may be a V-belt driving pulley or a motor secured directly to the line shaft, several advantages are gained. In the first place, when several machines are running and one is stopped for unloading the momentum of the active machines acts measurably as a fly wheel to accelerate the pick-up of the inactive machine when it is started in operation. Moreover, when the machine is disconnected from the line shaft, the braking action is more economical because there is no oversize motor of large mass to be retarded by the brake, as in the case of a directly-connected centrifugal drive. Both the clutch pulley 8 and the brake pulley 43 are readily provided with a water cooling circulation so that excessive heating of these frictional parts is prevented and injury to the driving belt or to an overheated motor is avoided. The casing 5 makes a complete enclosure for lubricating oil, so that there is no objectionable heat generated by the driving gears, and as the driving coupling between the spindle 32 and the basket shaft of the centrifugal takes place at the level of the center of gyration no heat is generated at that point.

The apparatus disclosed and claimed in the present application is particularly well suited for use in practicing improved methods of centrifuging sugar which involve subjection of massecuites and magmas to high centrifugal forces and novel control over the acceleration of the centrifugals, together with control over other treatments connected with centrifuging, to secure most efficient elimination of syrups and improved results from washing and syrup-separating operations. It is also well suited for other types of treatment, on mixtures of sugar crystals and syrup and in other fields where efficient separation of constituents of mixtures may be effected by centrifugal force.

The arrangement and construction of apparatus disclosed in my prior Patent No. 1,826,675, while effective at the lower centrifugal speeds in common vogue at the time said invention was made, is not suited for operations involving rapid acceleration to high speeds such as I have actually obtained with the present invention, partly because the energizing clutch used on the line shaft was of the wedging or clamping type so that when the clutch was set to active position it would result in so suddenly gripping the driving gear to the line shaft that it was necessary to use a slip clutch intermediate the vertical transmission shaft and the centrifugal, and a slip clutch of this type would involve too much lost motion to accelerate the loaded centrifugal quickly enough to make possible the attainment of such high speed within the time limited as is effected by my present construction. It will be noticed that when the driven member of the clutch on the line shaft is energized in the present construction the further transmission of power to the centrifugal itself is effected through positive coupling means. It is therefore highly important when rapid acceleration is employed that the pick-up of the power transmitting means should be very smooth to avoid breakage of the gears from any sudden powerful shock such as might be caused by the sudden gripping or wedging of the clutch mechanism employed in my earlier type of construction.

I recognize that particular parts and details of construction of the improved driving means for

centrifugal machines may be substituted by equivalents and in many instances omitted altogether without sacrificing advantages of the invention. I therefore desire that the invention be accorded a scope commensurate with the spirit of the specification as restricted only by the requirements of the claims.

What I claim is:

1. A driving mount for centrifugals embracing in combination with an overhead horizontal continuously rotating line shaft, a series of gyratory centrifugals suspended beneath it and a series of vertical non-gyratory transmission shafts intermediate the centrifugals and the line shaft, means for positively but flexibly coupling the transmission shafts with their respective centrifugals to cause their rotation in unison and drive transmitting mechanism for each centrifugal comprising centrifugally actuated clutch shoes having pivotal connections with the line shaft to revolve therewith and retractable at will to inactive position while revolving, a clutch pulley and a connected gear element loosely mounted on the line shaft and arranged to be energized at a progressively accelerating speed when the clutch shoes are released from retracted position, and a gear secured to the transmission shaft in mesh with the aforesaid gear.

2. In a driving mount for suspended gyratory centrifugals the combination with a continuously rotating line shaft, a centrifugal clutch member comprising centrifugally actuated clutching members connected to the shaft for rotation in unison therewith, and a driven friction pulley loosely mounted upon the shaft, a relatively large bevel gear securely connected with the pulley, a vertical non-gyratory transmission shaft below the line shaft having positive but flexible coupling connection with a centrifugal suspended beneath in coaxial alignment therewith, and a relatively small bevel gear secured to the upper end of said transmission shaft and in constant mesh with the aforesaid large gear.

3. A driving mount for centrifugals comprising a continuously running horizontal line shaft and a series of gyratory centrifugals suspended at a distance below said shaft, the line shaft comprising a series of individual sections coupled together end to end by flexible coupling members, a drive transmission mechanism comprising a vertical non-gyratory shaft arranged intermediate the line shaft and the centrifugal and having flexible but positive driving coupling with said centrifugal, a gear train comprising a relatively large bevel gear loosely revoluble about a section of the line shaft and meshing with a relatively small bevel gear on the transmission shaft, and a rotatable driving member connecting said gear train with a centrifugal clutch mechanism carried by the line shaft section upon which the large bevel gear is loosely mounted.

4. A driving mount for centrifugals embracing in its construction a supporting bed plate provided at its opposite end portions with axially aligned anti-friction bearings for supporting an individual section of a line shaft, the support for one of said anti-friction bearings comprising a hollow casing in which is mounted a relatively large bevel gear loosely revoluble about the line shaft, a clutch pulley mounted outside of said casing and adjacent thereto and secured to said gear by means of a connecting loosely revoluble sleeve, centrifugally actuated clutch shoes retractably mounted interiorly of said pulley and having pivotal connections with a driving spider

secured to the shaft section, a vertical transmission shaft mounted in said casing and carrying a relatively small bevel gear in mesh with said large bevel gear, said transmission shaft being provided with means for positively but flexibly coupling it with an underneath suspended centrifugal.

5. A driving mount for centrifugals embracing a single bed plate provided at its opposite ends with upwardly projecting anti-friction bearing supporting members, a horizontal line shaft section mounted therein and provided with means for coupling it to a similar adjacent section, said bed plate being provided with a depending socket hanger for the suspension of a gyratory centrifugal and being also provided with upper and lower anti-friction bearing members for supporting a vertical drive-transmitting shaft having flexible coupling connection with the centrifugal suspended beneath it, a centrifugally actuated clutch mounted upon said horizontal shaft to energize at will a large bevel gear also mounted on said shaft, said gear having driving connection with a relatively small gear secured to said transmission shaft, said gears and transmission shaft being mounted in a hollow casing forming one of the supports for the anti-friction bearing supporting said horizontal shaft.

6. A driving mount for centrifugal machines embracing in combination a series of suspended gyratory centrifugals, an overhead line shaft comprising individual sections for each centrifugal flexibly coupled together, each section being provided with its own individual bearing support, a centrifugally actuated clutch mounted on each section, the driven member of which has driving connection with a bevel gear train, and a line shaft powering element located intermediately of the series of centrifugals, thereby permitting the centrifuging operations to be continuously performed by the centrifugals on one side of the powering element while centrifugals on the other side thereof are inactive.

7. Driving means for a suspended gyratory centrifugal comprising a non-gyratory transmission shaft co-axially arranged above the centrifugal and flexibly coupled therewith, and an overhead continuously rotating horizontal power shaft having interruptible driving connection with the transmission shaft by means of a centrifugal clutch device mounted on the line shaft, the driven member of which clutch is directly connected with a bevel gear transmission train proportioned to transmit from the line shaft to the transmission shaft multiple speed rotation.

8. In a driving unit for a suspended gyratory centrifugal, the combination of a driving member rotatable about a substantially horizontal axis, a vertical non-gyratory transmission shaft interconnected with the driving member by bevel gearing, a gyratory centrifugal basket-carrying shaft suspended for gyration and rotation about a center in coaxial alignment with said transmission shaft, and flexibly interlocking coupling members for positively transmitting rotation to the basket shaft at substantially the level of the center of gyration.

9. In a driving unit for a gyratory centrifugal, the combination of a gear casing having bearing supporting openings bored at right angles to each other, anti-friction shaft bearing elements mounted in the respective bearing openings, a horizontal rotatable driving member supported in one bearing element, a vertical non-gyratory transmission shaft revolvably mounted in another

bearing element, a centrifugal basket spindle suspended to gyrate and rotate about a center below said vertical shaft and in coaxial alignment therewith, and flexibly but positively interconnected 5 coupling members secured to the transmission shaft and spindle for positively transmitting rotation to the basket spindle at substantially the level of said center of gyration.

10. Apparatus for driving a series of suspended 10 gyratory centrifugals comprising a common line shaft located adjacent a plurality of centrifugals of a series, means for powering said line shaft, a driving unit intermediate the line shaft and each of said centrifugals, said driving unit comprising a vertically extending transmission shaft, a driving member rotatable about an axis at an angle to the axis of said transmission shaft and intermeshing gears connecting said transmission shaft and driving member together for simultaneous rotation, means positively and constantly 15 coupling each of said transmission shafts with a gyratory centrifugal spindle, and power transmitting means interruptibly connecting each of said rotatable driving members with said line shaft to transmit power from the line shaft 20 through said driving units to said spindles.

11. In a driving unit for a gyratory centrifugal, the combination of a casing having seats for shaft bearings with axes at an angle to each other, 25 anti-friction shaft bearings mounted in said seats, a horizontally extending rotatable driving member supported on bearings in one of said seats and extending outside of the casing, the extended portion of said member embodying 30 means for positive connection with power transmitting means, a vertical non-gyratory transmission element supported on bearings in another of said seats and extending below the driving member at an angle thereto, means flexibly 35 but positively and constantly coupling the extended portion of said element with said spindle, and accurately intermeshing gears within said casing including a gear securely fastened to each of said driving member and transmission element.

45. 12. In a driving unit for a gyratory centrifugal, the combination of a casing having seats for shaft bearings with axes at right angles to each other, anti-friction shaft bearings mounted in said seats, a horizontal rotatable driving member 50 supported on bearings in one of said seats and extending outside of the casing, a pulley for transmitting power to the unit, disconnectible coupling elements on the extended portion of said driving member and said pulley fastening the 55 same together, a vertical non-gyratory trans-

mission shaft supported on bearings on another of said seats and extending outside the casing at right angles to the driving member, a suspended gyratory basket-carrying spindle, means flexibly but positively and constantly coupling the extended portion of said shaft with said spindle, and a pair of accurately intermeshing bevel gears within said casing including a gear securely fastened to each of said driving member and shaft.

10. 13. In a driving unit for a gyratory centrifugal, the combination of a mounting and enclosing casing for the unit made of upper and lower mating unitary sections, the lower section forming an integral bed support for other parts of the unit and having footings for anchorage to supporting framework above a suspended gyratory centrifugal, said casing having precisely machined openings with their axes in angular relation, a non-gyratory transmission shaft extending vertically into the casing through one of said openings and maintained in accurate position by spaced anti-friction shaft bearings seated in parts of the casing, an underneath gyratory basket-carrying spindle, means outside the casing 25 positively and constantly coupling said shaft with said spindle, a bevel gear secured to the shaft within the casing, a rotatable driving member extending into the casing at an angle to said shaft through another of said openings and maintained in accurate position by other spaced anti-friction bearings seated in parts of the casing, said driving member embodying means outside the casing for connection to power transmitting means, and a second bevel gear secured to said 30 rotatable drive member inside the casing in precise meshing relation with the bevel gear on said shaft.

14. Driving means for centrifugal machines comprising a group of centrifugals each having a 40 suspended gyratory basket-carrying spindle, a common line shaft for the centrifugals of the group, powering means for revolving the line shaft, a driving unit positively and constantly coupled to each spindle, each unit including a 45 train of intermeshing gears and a horizontally extending rotatable driving member secured to one of said gears, and means interruptibly connecting each of said driving members with said line shaft, said connecting means being operative 50 when actuated to establish progressively increasing speed transmitting connections between the line shaft and each driving unit as well as a full speed connection therebetween.

EUGENE ROBERTS. 55

CERTIFICATE OF CORRECTION.

Patent No. 2,128,575.

August 30, 1938.

EUGENE ROBERTS.

It is hereby certified that error appears in the printed specification of the above numbered patent requiring correction as follows: Page 6, first column, line 39, claim 11, after the comma and before "means" insert the words and comma a suspended gyratory basket-carrying spindle,; and that the said Letters Patent should be read with this correction therein that the same may conform to the record of the case in the Patent Office.

Signed and sealed this 13th day of December, A. D. 1938.
